UNITED STATES PATENT OFFICE.

EDWARD P. SHELDON, OF NEW YORK, N. Y., ASSIGNOR TO R. HOE AND CO., OF NEW YORK, N. Y., A CORPORATION OF NEW YORK.

MACHINE FOR ASSEMBLING PRINTED PRODUCTS.

1,008,567.

Specification of Letters Patent. Patented Nov. 14, 1911.

Application filed March 12, 1910. Serial No. 548,785.

To all whom it may concern:

Be it known that I, EDWARD P. SHELDON, a citizen of the United States, residing at New York, county of Kings, and State of New York, have invented certain new and useful Improvements in Machines for Assembling Printed Products, fully described and represented in the following specification and the accompanying drawings, forming a part of the same.

This invention relates to machines for assembling printed products.

In an application filed of even date herewith, said application being serially numbered 548,786 there is disclosed a machine for assembling printed products consisting of sheets obtained from a web or webs printed on a high speed web press and other sheets differing from the web sheets either in the character of the paper, or in the character of the printing, or both, and termed, for convenience, "inset" sheets. The specific machine disclosed in said above application produces a product in which the inset sheets always form the inside sheets of the product. In the machine disclosed in said application, furthermore, the inset sheets are formed from a multilength sheet which is presented to a cutting device of such a character that the sheets are required to be stopped during the cutting operation.

It is one of the objects of this invention to produce an improved mechanism for assembling printed products comprising web sheets and inset sheets, the mechanism being of such a character that the inset sheets may be placed either inside the web sheets or between the web sheets or both inside and between the web sheets.

40 A further object of the invention is to provide an improved mechanism for producing a combined product consisting of web sheets and inset sheets formed from a multilength sheet, the devices for forwarding the multilength sheets including a cutting mechanism of such a character that the sheets may be cut on the run.

With these and other objects not specifically referred to in view, the invention consists in certain constructions, and in certain parts, improvements and combinations as will be hereinafter fully described and then specifically pointed out.

Referring to the accompanying drawings—Figure 1 illustrates in side elevation

so much of a mechanism embodying the invention as is necessary to an understanding thereof. Fig. 2 illustrates a modified form of the construction shown in Fig. 1.

Machines embodying the invention will include suitable web forwarding devices which may be those usually employed to forward a plurality of webs printed on a high speed printing machine. In the particular machine illustrated, these web forwarding devices are indicated by the ordinary bending rolls 1 and nipping rolls 2 commonly used in high speed printing machines. The web or webs forwarded by the forwarding devices may be severed into sheets in any approved way. In the particular construction shown, this is effected by a pair of cutting rolls 3 of the usual type, one of these rolls being provided with knives 4 and the other with cutting blocks or woods 5, as is usual in such constructions.

Machines embodying the invention will include sheet feeding means for forwarding sheets which have been before referred to and termed for convenience "inset" sheets. 80 These means may differ widely in their construction and character. Referring more particularly to Fig. 1, said inset sheets are fed to the mechanism by feeding rolls 6, 7 which forward the sheets into the range of a drop roll 8 with which co-operates a driven roll 9, the construction being a common one in sheet feeding mechanism. In the particular machine illustrated, two such drop rolls are employed, the second drop roll 10 90 co-operating with a driven roll 11. The means for operating these rolls is indicated, but as it is common in the art, a description thereof is unnecessary.

In the particular machine illustrated, the inset sheets are formed from multilength sheets, and in machines in which such sheets are fed, mechanism should be provided for severing the sheets into sheet lengths. This mechanism, in machines embodying the invention in its best form will be of such a character that the sheets may be cut on the run. While the mechanism employed may be varied in its character, in the particular machine illustrated, the severing of the 100 multilength sheets is effected by cutting cylinders 12, 13, the cylinder 12 carrying the usual knife 14 and the cylinder 13 the usual co-operating block or wood 15.

Machines embodying the invention will 110

usually include timing devices so that the inset sheets referred to may be presented at the right time to be properly assembled with the sheets cut from the web or webs, thus enabling an assembled product to be produced the sheets of which are in register. While these timing devices may be variously located, in the particular machine illustrated, they operate upon the inset sheets prior to 10 the time said sheets are cut. The construction of these timing devices may, of course, be varied. As shown, they include a pivoted sheet stop 16 of a usual type mounted on a rock-shaft 17, this stop coöperating 15 with the drop rolls before referred to to time the sheets.

Where, as in the particular machine illustrated, the inset sheets are formed from a multilength sheet, and it is desired that the 20 mechanism simultaneously present a number of inset sheets for assembling with the web sheets, means should be provided for superposing the sheet lengths cut from the multilength sheet. Mechanism for thus 25 superposing sheets formed from the multilength sheets may be varied in character, and two constructions for effecting this result are illustrated.

Referring more particularly to Fig. 1, the 30 sheets after passing between the cutting cylinders 12, 13 are forwarded beneath a guide, as 18, to a roll 19 provided with a nipping jaw 20 backed up by a spring rod 21 of the usual type. This roll 19 coöperates with a 35 roll 22 provided with the usual tucking blade 23 which inserts the edge of the sheet into the bite of the jaw 20. To insure that the edge of the sheet gets into the nipping jaw 20, there may be employed a pivoted 40 guide, as 24, hung on a shaft 25 which is operated through an arm 26 by a cam 27 on a shaft 28. With this construction, the leading end of the multilength sheet is taken by the nipping jaw,—the guide 24 being 45 dropped to insure this,—and the sheet carried around by the roll 22. At about the time the nipping jaw takes the leading end of the multilength sheet, the sheet is severed, and, as the second part of the sheet comes 50 into proper position, the sheet which has been carried around by the roll 22 is laid upon it, the nipping jaw being actuated to release the sheet. To insure the forwarding of this sheet, after the nipping jaw has released it, a roll, as 29, may be employed, this roll being mounted on a shaft 30 hung in arms 31 supported on brackets 32 on standards rising from the frame. When the sheets have been thus superposed, they are, 55 in the particular machine illustrated in this figure, forwarded by the rolls 19, 22,—the position of the guide 24 being shifted to permit this,—into the bite of rolls 34, 35, which deliver the sheets for assemblage with 60 the web sheets formed by the cutting cylinder 36.

ders 3. The roll 35 has coöperating with it a roll, as 36, these rolls operating not only to receive and forward the web sheets which are delivered to them from the cutting cylinders 3, but also the inset sheets referred to. The roll 35 is, in the particular machine shown, provided with a cut away part 37, the purpose of which will be hereinafter explained.

In machines embodying the invention in 75 its best form, the mechanism for assembling the product will include a sheet receiving cylinder 38 which, as shown, is a three-part collecting cylinder. This cylinder, when employed, will, in the best constructions embodying the invention, be provided with sheet taking and holding devices. While these sheet taking and holding devices may be varied, they will, when a collecting cylinder of the character referred to is employed, in the best constructions embodying the invention, comprise two sets of grippers, a set for taking the product presented to the cylinder and a second set for holding the product while the first set is taking, so 80 as to insure the proper register of the superposed collected products. In the particular construction illustrated, the product is taken by a set of grippers 40, these grippers being mounted on a shaft 41 provided with an operating arm 42, as usual in gripper constructions, a roll on the arm 42 being arranged to contact at proper times with actuating cams. In the particular construction illustrated, the roll on the arm 42, as 85 the grippers approach the taking point, contacts with a cam 43 which operates to rock the shaft 41 and open the grippers, so that the product presented to the cylinder may 90 be taken by them.

The holding grippers before referred to are indicated at 44, these grippers being mounted on a shaft 45 supported in arms 46 in turn mounted on a shaft 47 having an operating arm 48 attached thereto. The shaft 45 may have an operating arm for opening the grippers and a spring for closing them, as common in gripper constructions, the illustration of these parts being omitted in the interest of clearness. The arm 48 carries a 100 roll which contacts with a cam 49 fixed on the frame of the machine. For convenience, this cam may be located at the point at which the sheets are to be finally delivered.

With the construction so far described, 105 the grippers 40 take the sheets after they pass between the rolls 35, 36 and carry them on around the cylinder 38, the sheets being laid over the tops of the grippers 44. As the cylinder 38 rotates, the roll on the arm 48 of 110 the shaft 47 which operates the grippers 44 strikes the cam 49 and withdraws these grippers from under the heads of the sheets which have been taken by the grippers 40, 115 after which the grippers 44 close down upon 120 the sheets.

the sheets so that the sheets are held by both sets of grippers. As the cylinder continues its rotation, the roll on the arm 42 strikes the cam 43 and opens the set of grippers 40 to take the fresh lot of sheets delivered by the rolls 35, 36. This operation continues until it is desired to deliver the sheets, at which time both sets of grippers will be opened.

10 The sheets may be delivered in any suitable manner. In the construction illustrated, they are delivered to a cylinder 50 provided with a set of grippers 51, these grippers being opened by a cam 52 on the frame of the machine. After closing upon the sheets, these grippers are opened again by a cam 53, and the sheets, in the particular machine illustrated, are delivered to a set of forwarding tapes 54. A switch, as 55, may be employed to insure delivery of the sheets.

15 Should it be desired to produce a product having a cover, the covers may be fed in by rolls 56, 57, the roll 57 having a raised surface 58 to enable the covers to be intermittently fed. The roll 57 delivers the covers in such a way that the head of the cover is in register with the sheets which have been delivered by the rolls 35, 36, the cover and these sheets being taken by the grippers 40.

20 Should it be desired to secure the product together by staples, this may be accomplished by providing a roll 59, this roll carrying a stapling mechanism of ordinary construction, indicated at 60, and co-operating 25 with the cylinder 38. Stapling mechanisms designed to insert the desired number of staples are well-known in the art and a specific description of such mechanism is unnecessary.

25 It has heretofore been stated that the roll 35 is provided with a cut-out portion 37. In order to give the grippers time to operate between the successive sets of sheets presented by the rolls 35, 36, it is desirable to 35 space the sheets apart. This may be done by causing the rolls 38, 57 to run at a slightly accelerated surface speed as compared with the rolls 35, 36, and the cutting away of the roll 35 as indicated at 37 enables the sheets, 50 after being taken by the grippers 40, to be pulled away from the rolls 36, thus spacing the sheets, as indicated in Fig. 1.

35 After the sheets have been stapled, they may, if desired, be subjected to the operation of a folding mechanism. While they may be folded by any desired mechanism, in the construction illustrated, a striker blade 61, operated in the usual manner, is illustrated for this purpose, the sheets being 40 presented to the striker blade by the tapes 54 before referred to and by a co-operating set of tapes 62, as is common in constructions of this character.

45 The construction illustrated in Fig. 2 shows a modified form of the mechanism for

superposing the parts of the multilength inset sheets. In this construction, after the head of the sheet has passed the cutting rolls 12, 13, it passes between the rolls 63, 64 with which co-operates a double switch 65 pivoted at 66, this switch being actuated in the usual manner by a construction well understood in the art and not illustrated. This switch directs the head of the sheet between a pair of rolls 67, 68, from which the sheet passes 50 between a pair of rolls 69, 70. The roll 63 may be cut away, as indicated at 71, to give space for the operation of the switch 65. The rolls 69, 70 have a slightly slower surface speed than the rolls which precede them, viz., the rolls 63, 64 and 67, 68, for the purpose of slowing down the sheet. When this construction is adopted the roll 69 may be cut away, as indicated at 72, so that no positive feeding action of this roll takes place 55 until after the tail of the sheet has passed between the rolls 67, 68 after which the high portion of the roll 69, together with the roll 70, takes control of the sheet and forwards it. As shown, the sheet, after it leaves the rolls 69 and 70, is taken control of by an angular guide 73 mounted on a cross-rod 74 and by a roller 75, these parts serving to direct the sheet downward to a pair of rolls 76, 77. 60

65 After the multilength sheet has been severed and the first part directed upward, by the switch 65, to the rolls 67, 68, and the agencies succeeding them, as described, the position of the switch 65 is shifted, lifting the tail of the first sheet upward, as shown, the cut-away portion 71 of the roll 63 facilitating this operation. The second half of the sheet is directed downward by the switch around the roll 64 and between rolls 78, 79 which serve to direct this sheet to the rolls 76, 77 before referred to where it meets the head of the first sheet. Tapes, as 80, passing around the rolls 77 and 79, may be employed for the purpose of supporting the sheet in 75 its transit from the rolls 78, 79 to the rolls 76, 77. The sheets thus assembled by the rolls 76, 77 are sent forward by these rolls to the rolls 34, 35 where they meet the incoming web sheets from the cutting rolls 80 85 before described.

80 The remainder of the mechanism has already been described in connection with Fig. 1 and further description of it is, therefore, unnecessary.

85 The gearing by which the operation of the several parts is effected is indicated, but as the operation of gearing of this character is well-known, it is unnecessary to burden the specification with the description thereof.

90 With the mechanism above described, and referring more particularly to Fig. 1, if it be desired to produce a twenty page product consisting of four four-page sheets and one four-page inset sheet, with the inset sheet 95

folded within the web sheets, a four page sheet—that is a sheet two pages wide and of the length of a page,—will be fed between the rolls 6, 7 and through the subsequent agencies, the jaw 20 on the cylinder 19 and the tucking-blade 23 on the roll 22 being rendered inoperative. The timing stop 16 will be set to so control the feed of the sheet as to cause it to meet the head of the web sheets as they pass between the rolls 35, 36. In the production of this product, one four-page sheet will be forwarded by the rolls 6, 7 for each four cuts from the web. It is apparent that the four page sheet with this arrangement of the construction will pass with the first cut from the web to the collecting cylinder 28 and will be laid on the naked surface of the cylinder, so that when the product is associated and folded, this four-page inset sheet will lie inside the web sheets. If, in addition, a cover be desired for this product, it will be fed between the rolls 56, 57, so as to be laid on the collecting cylinder with the fourth cut from the web. If it be desired to produce the product last described, that is to say, a twenty-page product consisting of four four-page sheets from the web and a four-page inset sheet, the inset sheet being between the web sheets, the sheet described as being fed between the rolls 6, 7 instead of being so fed as to meet the first cut from the web, will be fed so as to meet the second, third or fourth, according to the place where it is desired to insert the inset sheet.

If it be desired to produce a twenty-four page product having two four-page inset sheets, both of which are folded inside the web sheets, a multilength sheet will be fed and cut in the manner heretofore described, the first part of the multilength sheet being laid upon the second part by the cylinder 19, the jaw 20 of this cylinder and the tucking blade 23 in this arrangement being operative. The timing stop 16 will be so arranged as to cause the superposed parts of the multilength sheet to meet the first cut from the web.

It is apparent that by properly actuating the timing stop these two four-page inset sheets can be interleaved between the first and second, or the second and third, or the third and fourth, cuts of the web, in the manner heretofore described.

If it be desired to produce, say, a twenty-four page product having an inset sheet of four pages inside the web sheets, and a second inset sheet between the web sheets, a multilength sheet will be fed by the rolls 6, 7. In this arrangement, the jaw 20 on the cylinder 19 and the tucking blade 23 will be rendered inoperative, and the timing stop will be set so that the first half of the multilength sheet will meet the first cut from the web, and the second half of said

sheet will meet the second cut from the web. With this arrangement, a multilength sheet will be fed for each four cuts of the web. It will be apparent that the first half of the multilength sheet will form an inset sheet 70 lying inside of the first cut of the web, and the second half of the multilength sheet will form an inset sheet lying between the first and second cuts of the web.

Changes and variations may be made in 75 the construction by which the invention is carried into effect. The invention is not, therefore, to be confined to the particular constructions herein shown and described.

What is claimed is:—

1. The combination with web forwarding means, of devices for severing sheets therefrom, inset sheet feeding means, and means for assembling the sheets forwarded by said inset sheet feeding means with the web 85 sheets to form a combined product which has said inset sheets inside the web sheets, or between the web sheets, or both inside and between the web sheets.

2. The combination with web forwarding 90 means, of devices for cutting sheets therefrom, inset sheet feeding means, cover feeding means, and means for assembling the sheets forwarded by the inset and cover feeding means with the web sheets to form 95 a combined product which has the inset sheets inside the web sheets, or between the web sheets, or both inside and between the web sheets, and has the cover applied to the outside of said sheets.

3. The combination with web forwarding means, of devices for severing sheets therefrom, inset sheet feeding means, means for assembling the sheets forwarded by said inset sheet feeding means with the web sheets 105 to form a combined product which has said inset sheets inside the web sheets, or between the web sheets, or both inside and between the web sheets, and devices for stapling the combined products together.

4. The combination with web forwarding means, of devices for cutting sheets therefrom, inset sheet feeding means, cover feeding means, means for assembling the sheets forwarded by the inset and cover feeding 115 means with the web sheets to form a combined product which has the inset sheets inside the web sheets, or between the web sheets, or both inside and between the web sheets, and has the cover applied to the outside of said sheets, and devices for stapling the combined product together.

5. The combination with web forwarding devices, of devices for cutting sheets from a web or webs forwarded thereby, intermittently operated inset sheet feeding means, intermittently operated cover feeding means, a collecting cylinder to which the various sheets are presented, and means for so controlling the presentation of the inset and 130

cover sheets, with respect to the web sheets as to cause the cylinder to collect a combined product having the cover sheet on the outside, and the inset sheets inside the web sheets, or between the web sheets, or inside and between the web sheets.

6. The combination with web forwarding devices, of devices for cutting sheets from a web or webs forwarded thereby, intermittently operated inset sheet feeding means, intermittently operated cover feeding means, a collecting cylinder to which the various sheets are presented, means for so controlling the presentation of the inset and cover sheets with respect to the web sheets as to cause the cylinder to collect a combined product having the cover sheet on the outside, and the inset sheets inside the web sheets, or between the web sheets, or inside and between the web sheets, and devices for stapling the combined product.

7. The combination with web feeding devices, of means for severing sheets from a web or webs forwarded thereby, means including timing devices for forwarding and controlling a multilength sheet, devices for severing said sheet into sheet lengths, a collecting cylinder, and means for intermittently presenting to the collecting cylinder sheets from the multilength sheet feeding devices simultaneously with the web sheets.

8. The combination with web feeding devices, of means for severing sheets from a web or webs forwarded thereby, means including timing devices for forwarding and controlling a multilength sheet, devices for severing said sheet into sheet lengths, a collecting cylinder, means for intermittently presenting to the collecting cylinder sheets from the multilength sheet feeding devices simultaneously with the web sheets, and means for intermittently presenting an outside or cover sheet to the collecting cylinder.

9. The combination with web feeding devices, of means for severing sheets from a web or webs forwarded thereby, means including timing devices for forwarding and controlling a multilength sheet, devices for severing said sheet into sheet lengths, a collecting cylinder, means for intermittently presenting to the collecting cylinder sheets from the multilength sheet feeding devices simultaneously with the web sheets, means for intermittently presenting an outside or

cover sheet to the collecting cylinder, and devices for stapling the combined product.

10. The combination with web forwarding means, of devices for severing a sheet or sheets from the webs forwarded thereby, a collecting cylinder to which the web sheets are delivered, means located on the collecting cylinder side of the web sheet path for feeding multilength sheets, and means for severing said multilength sheets into sheet lengths while the sheets are in motion, said multilength-sheet feeding means operating to present sheets intermittently to the collecting cylinder but simultaneously with the web sheets.

11. The combination with web forwarding means, of devices for severing a sheet or sheets from the webs forwarded thereby, a collecting cylinder to which the web sheets are delivered, means located on the collecting cylinder side of the web sheet path for feeding multilength sheets, means for severing said multilength sheets into sheet lengths while the sheets are in motion, said multilength-sheet feeding means operating to present sheets intermittently to the collecting cylinder but simultaneously with the web sheets, and means for intermittently presenting outside or cover sheets to the collecting cylinder.

12. The combination with web forwarding means, of devices for severing a sheet or sheets from the webs forwarded thereby, a collecting cylinder to which the web sheets are delivered, means located on the collecting cylinder side of the web sheet path for feeding multilength sheets, means for severing said multilength sheets into sheet lengths while the sheets are in motion, said multilength-sheet feeding means operating to present sheets intermittently to the collecting cylinder but simultaneously with the web sheets, means for intermittently presenting outside or cover sheets to the collecting cylinder, and means for stapling the combined product.

In testimony whereof, I have hereunto set my hand, in the presence of two subscribing witnesses.

EDWARD P. SHELDON.
